UNITED STATES PATENT OFFICE.

GEORGE P. ROSE, OF FENTON, MICHIGAN.

RAILWAY SPLICE-BAR.

SPECIFICATION forming part of Letters Patent No. 395,923, dated January 8, 1889.

Application filed May 31, 1888. Serial No. 275,556. (No model.)

To all whom it may concern:

Be it known that I, GEORGE P. ROSE, a citizen of the United States, residing at Fenton, county of Genesee, State of Michigan, have invented a new and useful Railway Splice-Bar, of which the following is a specification.

This invention has for its object certain improvements, substantially as below described and claimed.

10 In the drawings forming a part of this specification, Figure 1 is a perspective view; Fig. 2, a plan with part in section on the dotted line 2 2 in Fig. 1; Fig. 3, a cross-section on the dotted line 1 1 in Fig. 2; and Fig. 4 shows the end 15 of a rail at the joint in perspective.

Referring to the letters marked on the drawings, A are the rails of a railway cut obliquely at the end, as at C, at the joint of the rails. By this means the wheels of the cars bear on solid 20 rail all the way over the joint, thus obviating the jarring and clicking caused by having the joint or space between the rails straight across.

The splice-bars B fit the hollow sides of the rails, but do not extend beneath the rails, as 25 in another pending application, Serial No. 275,555, but they gradually grow thinner from the center toward the ends to proportion the strength in accordance with the needs, and the bolts which secure the bars to the rails 30 are graduated as to size, the largest bolt being at the center, as in said other application and for the same reasons therein given, and one of the splice-bars—the outside one—has like threaded holes. The ends of the bolts 35 are screw-threaded and lock-nuts are screwed

onto said ends, as in the other application referred to. (See Fig. 3.)

The splice-bars B are re-enforced at the center, where the joint of the rails comes, Fig. 3, nearly or quite filling the space beneath the 40 flanges of the tread part of the rail. On the outside the bar B is still greater re-enforced by the elongated boss a', Figs. 1 and 3. The reason that the inside bar at a'' is not provided with the boss is that it might interfere 45 with the flange of the car-wheel. The center holes for bolt x pass through the re-enforced parts a' a and through the slots e in the joint end of the rails, Fig. 4. Providing the splice-bars with this extra re-enforcement at the 50 joint, and one of them with the re-enforcing boss, greatly strengthens the bars at the joint and compensates for the weakening of the bars at this point caused by the center bolt-holes. 55

Having thus described my invention, what I claim, and desire to secure by Letters Patent, is—

The combination of the rails having the oblique lapping ends, the splice-bars re-enforced 60 at the center and the outer one being provided with the boss, and the securing-bolts, substantially as set forth.

In testimony of the foregoing I have hereunto subscribed my name in presence of two 65 witnesses.

GEORGE P. ROSE.
